SHADOW BOX

William F. Vernon, Newton, Iowa

Application January 17, 1947, Serial No. 722,649

1 Claim. (Cl. 41—34)

1

This invention relates to mounted pictures and particularly to the form of picture mounting generally described as shadow box. The usual form of shadow box is a rather shallow glass fronted box wherein an entire framed picture is enclosed for protection of both the picture and its frame and to lend an illusion of depth to the picture. To augment the illusion of depth sometimes objects such as stuffed birds or other objects complementary to the picture are inserted in the box. The shadows from such inserted objects falling on the picture heightens the illusion of depth and gives the mounting its name, "Shadow box."

Shadow box pictures are usually large and expensive, probably because the cost of the large glass fronted box is not justified except for such pictures. However, the artistic effect, including the illusion of depth, is highly desirable and adds to the artistic merit of smaller and cheaper pictures.

It is the particular object of the present invention to provide a glass fronted shadow box mounting for pictures that is artistic, light, and inexpensive.

Another object is to provide a shadow box mounting for pictures wherein the usual picture frame is entirely eliminated, although the general appearance and advantages of the frame are retained.

A further object is to provide on the glass front for the shadow box complementary decorations that will cast their shadows on the picture to heighten the artistic effect and augment the illusion of depth.

And a still further object is to provide in a shadow box picture as above described means to extend the picture completely around the inside of the box to the glass front of the box to further augment the illusion of depth in the picture.

Other objects and benefits will be disclosed in the following descriptions and drawings in which

Fig. 1 is a front elevation view of a mounted plate against the wall of a shadow box picture which will be utilized to illustrate the invention;

Fig. 2 is a top plan view of the shadow box picture as shown in Fig. 1;

Fig. 3 is an enlarged broken cross sectional view of the shadow box picture as it would appear on the section line 3—3 of Fig. 1;

Fig. 4 is an exploded isometric view of the shadow box picture as will later be explained;

Fig. 5 is an enlarged cross sectional view of a cord mounting of the shadow box picture as it would appear on the section line 5—5 of Fig. 4;

2

Fig. 6 is an enlarged broken plan view of the developed dual box element as it would appear on the corner section 6—6, Fig. 4, as will later be explained; and

5 Fig. 7 is a top plan view of the shadow box picture as mounted in a corner or against a flat wall.

Now referring to the drawings, it will be observed that the face glass front 10 actually forms 10 the base of my improved shadow box because all other elements are attached to and are held together by the face glass front. On the back of the base, following a general frame-like contour around the edge, is a multi-colored paint film 15 element 11 having a general black background 11—a, an outside Indian red border line 11—b and an inside Indian red border line 11—c with black decorative figures 11—d, which in this particular picture represent cattle brands. Inside 20 of the border 11—c are black and red painted figures, 11—e is the well known type of cook wagon used by cattlemen and the figures of such cattlemen, 11—f, around a camp fire 11—g. These foreground figures complement the picture background 12 which represents in this instance a 25 timberline camp for cattlemen in what appears to be the Rocky Mountain region.

Now referring to Fig. 3, the aforementioned timberline camp picture is printed on flanged 30 paper 13 affixed to the inside of a stiff paper flange box element 14 and both securely glued on the flanges to the back of the glass member 10. The entire shadow box picture is supported on a cord 15 inserted through holes 16 and 17 through the 35 cardboard box member 14 but back of the picture 13.

Now referring to Figs. 4, 5 and 6, it will be observed that the flanged box members 13 and 14 are held together in flanged open box relationship by tapes 18 on the corners. As shown in Fig. 5, the cord 15 passes through holes 16 and 17 in the stiff support member 14 but inside of the paper picture member 13. Thus the support cord member 15 is entirely concealed from view 45 through the glass 10. It will be understood and appreciated that the dual members 13 and 14 exactly coincide with each other when in flat doubled relationship, and that each of them have the flat side and flanged elements 13, 14, the box side elements 13s, 14s, and the flange elements 13—f and 14—f as clearly shown in Fig. 6. When in flat relationship, the elements 13 and 14 are 50 lightly glued together so that when the open flanged box element is glued to the inside face 55 11 of the base member 10 the picture 13 as viewed

through the open center section of the glass will extend completely around the inside wall of the box-like structure and up to the inside face of the glass 10. This is an important feature of my improvement in this art because it adds to the illusion of depth by permitting observation of the side elements of the picture 13—s extending from the back of the box completely up to the inside face of the glass.

Now referring again to Fig. 1, it will be appreciated that the figures 11—e, 11—f and 11—g extending over the exposed face of the glass 10 will naturally cast shadows inwardly and on the background picture 12 when light is directed toward the picture. In this particular picture 12 which is entitled Timberline, this arrangement gives the illusion that this group of cowboys are camping on the shores of a stream or small lake near the timberline of a mountain range. The shadows augment the illusion of depth and the general combination of the background, the cowboys and the cow brands illustrated in the border 11—c, coact with each other to produce a highly artistic effect.

Now referring to Fig. 7, it will be observed that my mounting cord 15 through the holes 16 and 17 can be utilized to either hang the picture flatly against the wall F—W or in abutting corner relationship in a corner C by hook 15—h. This arrangement is advantageous because various lighting conditions in the room can be utilized to cast the shadows where the best artistic effect may be obtained.

Consideration of this structure will show that I have provided a light, inexpensive but effective shadow box picture mounting. The structure is so inexpensive that small printed pictures may be effectively mounted and the general artistic effect of such small pictures heightened and augmented by the adaptation of the general shadow box mounting idea in this light, inexpensive structure.

Having thus explained my invention, I now claim as new:

A shadow box pictorial display comprising a transparent glass front, a box of predetermined depth secured to said front and comprising a stiff paper backing, a picture secured thereto, and portions of said backing and picture being provided with offset flanges for attachment directly to said glass front whereby said picture forms a continuous backdrop spaced from said glass front and leading directly thereto, and said glass front having a plurality of opaque foreground objects secured thereto in complement with respect to the picture backdrop including an opaque design to completely hide the attached portions of the box adjacent the glass front, and concealed means attached to the stiff paper backing of the box for supporting the entire unit from a wall support comprising a hanging cord, spaced apertures in said stiff paper backing to receive said cord, the latter having a portion thereof connected with said box between said stiff paper backing and said picture to emerge through said apertures to form an outside supporting loop, said picture concealing the connected portion of said loop.

WILLIAM F. VERNON.
